United States Patent Office

Des. 198,634
Patented July 14, 1964

198,634

TREE STAND

Zdenek Ch. Newman, 7375 Woodward Ave.,
Detroit, Mich.

Filed Sept. 6, 1961, Ser. No. 66,623

Term of patent 14 years

(Cl. D35—3)

FIG. 1 is a top plan view of tree stand, showing my new design, two of the legs being broken away for convenience of illustration;

FIG. 2 is a vertical sectional view thereof taken on line 2—2 of FIG. 1; and

FIG. 3 is a fragmentary side elevation of the upper portion thereof taken on line 3—3 of FIG. 2.

I claim:

The ornamental design for a tree stand, as shown and described.
